2,411,304

METHOD AND APPARATUS FOR LAPPING
DIES

Daniel D. Symmes, West Haven, Conn., assignor
to The American Steel and Wire Company of
New Jersey, a corporation of New Jersey

Application March 6, 1945, Serial No. 581,197

6 Claims. (Cl. 51—58)

1

The present invention relates to improvements in the method and means for lapping wire drawing dies or the like.

Among the objects of the invention are:

To obtain accurate control of the entrance and exit angles of the die perforation;

To obtain accurate control of the size of the diameter of the perforation;

To obtain precision control of the axial length of the bearing or throat portion of the die perforation;

To provide means for readily varying the axial length of the throat or bearing of the die perforation;

To obtain rounding in the region where the entrance and approach angles of the die opening merge with the bearing throat portion thereof;

To obtain with great precision any predetermined entrance and exit relief angles, diameter of the working throat portion, and length of said bearing or throat portion;

To provide precision mechanism for automatically performing the operations necessary to lap the perforation of a drawing die to a contour as viewed in longitudinal section, corresponding to two oppositely outwardly flaring straight-walled frusto-conical entrance and exit portions with a substantially cylindrical bearing portion of predetermined length between them.

It has been the common practice in the wire drawing industry for many years, to condition wire drawing dies by lapping the perforations of the dies. In the earlier days the die perforations were conditioned by manually controlled lapping operations, and expert die makers acquired great skill. Nevertheless, the human element entered into the operation, and the uniformity of die conditioning on a large scale was practically impossible. In other words, with the manually controlled operations it is difficult to produce a great quantity of dies having identically the same contour of perforation as viewed in longitudinal section. As the art progressed, different types of lapping or die conditioning machines were proposed. These usually involved rotating the die and reciprocating the lap through the perforation therein while at the same time varying the angularity of the lap with respect to the axis of the perforation. So far as I am informed, all such prior mechanical means have resulted in forming a die perforation which, when viewed in longitudinal section, corresponded to a parabolic curve. Thus the throat or working region of the die was in a

2

restricted zone or area, the wire being drawn making contact with a very short portion of the die.

Under my invention, as will hereinafter more fully appear, I propose to depart from the prior practice of relying upon the skill of the operator to determine the contour of the die perforation, and I also depart from the later practice which heretofore has resulted in producing a die having a parabolic contour as viewed in longitudinal section through the perforation. As pointed out more fully hereinafter, under my invention I so control the lapping operation that the lapping tool or needle is held or dwells at a predetermined angle for a predetermined time interval with respect to the longitudinal axis of the die perforation, and for another time interval I provide for holding the lapping tool or needle and causing it to dwell in a position substantially coincident with the longitudinal axis of the die-perforation. In this way I obtain a die perforation contour which as viewed in longitudinal section corresponds to two oppositely flaring straight-walled frusto-conical entrance and exit portions separated by a substantially cylindrical straight walled throat or bearing portion, and I provide means for accurately holding the lapping needle or tool in the desired positions for predetermined time intervals and also provide means for momentarily oscillating the lapping tool or needle for a short interval of time so as to round off the angular corners in the transition regions between the ends of the throat portion and the inner extremities of the outwardly flaring frusto-conical entrance and relief portions.

For a more complete understanding of the invention, reference should be made to the following detailed description, the accompanying drawings, and the appended claims.

In the drawings:

Figures 1, 2 and 3 illustrate different sequential steps in my improved method of die conditioning.

Figure 4 is a greatly enlarged view through the perforation of a wire drawing die made by the improved method and apparatus herein claimed.

Figure 5 is an enlarged detail view of a portion of apparatus used in carrying out the invention.

Figure 6 is an enlarged view illustrative of the action of the lapping tool or needle at the completion of the lapping of the oppositely flaring entrance and exit portions of the die perforation.

Figures 7, 8 and 9 are sections similar to Figures 1, 2 and 3 but omitting the lapping tool in

the interest of clarity in the designation of characteristics of different parts of the die perforation.

Figure 10 is a front elevation of a machine involving novel features of construction and arrangement designed for carrying out the herein claimed method.

Figure 11 is a plan view of Figure 10.

Figure 12 is an end elevation as viewed from the right end of Figure 10.

Figure 13 is a development of a control cam shown in Figures 10, 11 and 12, effective to maintain the die lapping tool or needle in predetermined positions.

Referring more particularly to the drawings, I have shown in Figure 4 a greatly enlarged view of a die having a perforation therein formed according to the herein claimed method and by the improved apparatus I have devised for carrying out the method. In this figure the die is shown with a 90° beveled portion 10 which may be molded, cast, or formed in any conventional manner since it forms no part of the invention. The invention has particular reference to the method and means for forming with great precision the oppositely flaring straight-walled entrance and exit portions 12 and 14 and the substantially cylindrical straight-walled throat or bearing portion 16 located intermediate such entrance and exit portions.

As shown in Figure 4, the entrance and exit portions 12 and 14 form straight-walled oppositely flaring frusto-conical cavities separated by the bearing portion 16 which is straight-walled and substantially cylindrical, although, as will herein-after appear, the throat or bearing portion 16 may have a slight taper corresponding to that of the particular lapping tool or needle used.

According to my improved method of die lapping, I start with a die having a roughly formed perforation therein of approximately the shape shown in Figure 4. This may be a new die, or it may be one that has been in use and requires refinishing. In carrying out the improved method I employ a lapping tool or needle such as indicated at 18, which has a long slender working portion 20 tapered, for example, to a 1° included angle. In starting the operation the lapping needle 18 is entered through the die perforation at a predetermined angle, and is charged with a suitable abrasive mixed with kerosene oil, olive oil, or the like. The lapping needle is clamped by chuck 22 to a spindle 24 carrying a collar 26 of such diameter that when inclined with its lower edge resting on top of a slide 28, the angle α between the axial center line $m-n$ of the lapping tool makes a predetermined angle with the axis $o-p$ extending longitudinally through the center of the die perforation. The die spindle 24 passes through a guide opening 27 in the slide 28. A weight 29 is secured to the lap so as to tend to move it downwardly. The lapping operation is complete when the collar 26 is moved downwardly by the weight 29 sufficiently to bring the lower face of said collar flush with the upper face of the slide 28, with the lap in the vertical position of Figure 2.

Reciprocating movements are imparted to the slide at predetermined time intervals through a follower 36 by a control cam 30 having dwell portions 32 and 34, as shown by the development in Figure 13. The dwell portion 32 serves to hold the lapping tool for a predetermined time interval in an angular position (for example, that of Figures 1 and 5) to suit the desired angle of the

entrance and exit portions, and the dwell portion 34 serves to hold the lap for a predetermined time interval in a position coinciding with the longitudinal axis of the die perforation as indicated in Figure 2. The cam also has an undulated portion including a rise 38 and a depression 40 effective to quickly shift the lap back and forth from the full line to the dotted line position of Figure 3, so as to cause the lap to round off the corners 13 at the transition regions where the entrance and exit portions 12 and 14 intersect the intermediate throat or bearing portion 16. These periodic dwells for the approach and relief angles and dwell for the throat size and oscillations for rounding the bearing corners, are recurrent throughout the entire die conditioning cycle, and while such operations are being periodically performed the cam 64 at the proper time imparts a vertical reciprocating motion to the slide 28 which in turn lifts and lowers the lap, thus avoiding ringing or scratching of the wall of the die perforation.

A tension spring 31 has one end secured to a rib depending from the slide 28 and the other end secured to a fixed anchorage, and thus tends to hold the cam follower 36 against the active face of the cam 30. The spindle 24 is conveniently formed of round tubing having a flattened face portion 25, for coaction with the flat face 27' of the aperture 27, so as to normally prevent turning of the spindle 24.

The die to be conditioned is mounted on a platen 42 and secured thereto in any suitable manner. This platen is rotatably supported on an antifriction bearing 44 and is adapted to be driven at a high rate of speed by a pulley 46 and a belt 48 trained around a pulley 50 carried on a shaft 52 driven by a motor 54 through a suitable reduction gear unit 56. The shaft 52 carries a worm 58 which meshes with and drives a worm wheel 60 secured to a shaft 62 mounted in suitable bearings as shown. This shaft carries a cam 64 which is adapted to rock a lever 66 secured to a rock shaft 68 carrying arms 70 which in response to movements of the cam 64 periodically lift and lower the slide 28, the latter being mounted in guide members 72 movable vertically in ways 74 formed at the upper extremity of fixed standards 76. In the machine illustrated the slide 28 is horizontally disposed and is periodically or intermittently shifted in a horizontal direction, under control of the cam 30, for certain predetermined distances to correspond with the particular angle α to suit the desired taper of the entrance and exit portions of the die under treatment. The cam 64 controls the vertical lowering and lifting of the slide 28, and this cam is preferably so designed that no vertical movement will be imparted to the slide 28 while the lapping tool dwells in the angular position of Figure 5. Preferably the vertical movement of the slide 28 is effected by the cam 64 during the time interval that the axis of the lapping tool 18 and its holder 24 is vertically positioned coincident with the axis $o-p$ of the die perforation.

Proper coordination of the action of the cams 64 and 30 is readily secured, since the shaft which carries the cam 64 has secured near one extremity thereof a worm 78 which meshes with the worm wheel 80 which is keyed or otherwise secured to the shaft 82 on which the control cam 30 is mounted.

From the foregoing it is apparent that the machine shown and described has been especially constructed and arranged for carrying out my

improved method of die lapping. In this method of lapping, a great number of dies can be lapped simultaneously since the single control cam 30 will determine the angular disposition of a plurality of lapping needles 20 coacting with a plurality of dies carried by corresponding platens 42. Each die is placed on a corresponding platen 42. A collar 26 of a predetermined diameter is selected for the bearing length desired. This collar is slipped over the spindle 24 and is held thereon by a suitable set screw. As shown in Figure 5, the lower peripheral edge of the collar rests on the upper face of the slide 28. Since the collar is perpendicular to the axis $m-n$ of the spindle and lapping tool 18, the under face of the collar makes an angle with the upper face of the slide 28 which is equal to the angle between the lines $m-n$ and $o-p$. In the die illustrated this angle is 8.5° in each case. Thus the included angle of the entrance portion of the die with the setting shown will be 17° plus the 1° taper of the needle, or 18° , and the exit portion will be 17° minus 1° or 16° , all as indicated by way of example in Figures 4 and 6. As illustrated by way of example in Figure 5, the lower face of the collar 26 makes an angle x with the upper face of the slide 28 which is equal to the angle a between the lines $m-n$ and $o-p$. The length of the side of the triangle opposite the angle x is readily determined by trigonometry from the formula

$$b = r \text{ times tangent of } 8.5^\circ$$

r being the radius of the collar 26 which corresponds to the adjacent side of the angle x . With the lap 18 tapered to form a 1° included angle and extending for a uniform straight distance as at s in Figure 6, it is possible to accurately calculate the diameter d , Figure 6, at the plane in the die where the entrance and relief angles meet. The spindle axis in the example illustrated in Figures 5 and 6 being at an angle of 8.5° , a right triangle y is formed as indicated in Figure 6, whose hypotenuse coincides with the plane where the entrance and exit angles intersect. The distance the lapping tool 18 will finally enter the die is equal to the distance marked b' in Figure 6, which is the same as the distance b marked in Figure 5. With these angles and lap tapers, the longitudinal length or extent of the bearing portion indicated by the dimension line b_2 in Figure 4 will always be the same regardless of the throat diameter. If a longer or shorter bearing length b_2 is desired, a similar change in the collar radius r will accomplish the desired result.

Figures 7, 8, and 9 are longitudinal section representations of three faces of die perforation as the same is conditioned at different stages of my improved method.

Figure 7 illustrates the result of the first stage of the operation, after the lapping tool 18 has dwelt for a predetermined time interval; for example, at the 8.5° angle illustrated in Figure 1. In this figure it is noted that the upper frusto-conical entrance portion 12 is formed to an included angle one degree greater than the lower frusto-conical exit portion 14, due to the one-degree included angle between the opposed faces of the lapping needle. Obviously if the lapping needle were truly cylindrical and not tapered, the entrance and exit angles would be equal.

Figure 8 illustrates the condition of the die after the lapping tool 18 has dwelt for a predetermined time interval in a position in which its axis is coincident with the longitudinal axis of the die perforation, thus forming the substan-

tially cylindrical bearing or throat portion 16 as shown, which will have the slight taper corresponding to that of the tool 18, which is $1/2^\circ$ on each side of the center line, as shown, for example, in Figure 6.

Figure 9 illustrates the result of the oscillating action of the tool 18 after it has acted to round off the corners at the region where the approach and exit angles 12 and 14 meet the substantially cylindrical bearing portion 16 of the die.

The detailed features of the foregoing method and apparatus as described and illustrated are to be interpreted in an illustrative rather than a limiting sense, since various modifications may be made by those skilled in the art without departure from the spirit and scope of the invention as defined in the appended claims.

I claim:

1. In a machine for lapping drawing dies, a support adapted to carry a die having a perforation to be lapped to a predetermined contour as viewed in longitudinal section, a lapping needle whose end is adapted to project through the die perforation, means for effecting relative rotation between the support and the lapping needle, means for causing the lapping needle to dwell for a determined time interval at a predetermined angle to the longitudinal axis of the perforation in the die and then to move to a position coincident with said axis and dwell in said coincident position for a determined time interval whereby the perforation in the die is contoured by the action of said needle to conform to two straight-walled outwardly flaring frusto-conical entrance and exit portions separated by an intermediate substantially cylindrical bearing portion.

2. In a machine for lapping drawing dies, a rotatable support adapted to support a perforated die whose perforation is to be lapped to a predetermined contour as viewed in longitudinal section, a lapping needle whose end is adapted to project through the die perforation, means for causing the needle to dwell for a determined time interval at a predetermined angle to the longitudinal axis of the perforation in the die and then to move to a position coincident with said axis and dwell in said coincident position for a determined time interval whereby the perforation in the die is contoured by the action of said needle to conform to two straight-walled outwardly flaring frusto-conical entrance and exit portions separated by an intermediate straight-walled substantially cylindrical bearing portion.

3. In a machine for shaping wire drawing dies, a rotatable support adapted to hold a drawing die having a perforation therein to be lapped to a predetermined contour as viewed in longitudinal section, a holder carrying a lapping tool having an end portion projecting into the die perforation, a slide with which the holder contacts, a collar secured to the holder and adapted to coact with the slide and a cam for shifting said slide having one dwell portion effective to hold the slide in a position to incline the tool at a predetermined angle to the longitudinal axis of the die opening for a determined time interval and having another dwell portion effective to maintain the slide in another position to maintain the holder and the lapping tool carried thereby in a position for a determined time interval wherein their common axis coincides with the longitudinal axis of the die perforation, whereby the die is contoured by the action of said tool to conform to two straight-walled out-

70

75

wardly flaring frusto-conical entrance and exit portions separated by an intermediate straight-walled substantially cylindrical bearing portion.

4. In a machine for lapping wire drawing dies, a rotatable support adapted to hold a die having a perforation therein to be lapped to a predetermined contour as viewed in longitudinal section, a holder carrying a lapping tool having an end portion projecting into the die perforation, a slide with which the holder coacts, a collar secured to the holder and adapted to coact with the slide, and a cam for shifting said slide having one dwell portion effective to hold the slide in a position to incline the tool at a predetermined angle to the longitudinal axis of the die opening for a determined time interval and having another dwell portion effective to hold the slide in another position to maintain the holder and the lapping tool carried thereby in a position for a determined time interval wherein their common axis coincides with the longitudinal axis of the die perforation, whereby the die perforation is contoured by the action of said tool to conform to two straight-walled outwardly flaring frusto-conical entrance and exit portions separated by an intermediate straight-walled substantially cylindrical bearing portion, said cam also having an undulated portion effective to oscillate the lapping tool so as to round off the wall of the die perforation at the region of the intersections of said frusto-conical entrance and exit portions with said intermediate bearing portion.

5. In the lapping of drawing dies, the method which comprises providing a die having a longitudinal perforation including connecting oppositely tapered entrance and exit portions, rotating the die about the axis of the perforation thereof while subjecting the wall of the perfora-

tion to the action of an elongated substantially cylindrical lapping tool extending through the perforation and contacting said tapered entrance and exit portions, causing said tool first to dwell at a predetermined angle to the longitudinal axis of the die perforation for a predetermined time interval and later causing said tool to dwell in a position substantially coincident with said longitudinal axis of the die for a determined time interval, whereby the perforation in the die is accurately contoured to conform to two straight-walled outwardly flaring frusto-conical entrance and exit portions separated by an intermediate straight-walled substantially cylindrical bearing portion.

6. In the lapping of drawing dies, the method which comprises providing a die having a longitudinal perforation including connecting oppositely tapered entrance and exit portions, rotating the die about the axis of the perforation thereof while subjecting the wall of the perforation to the action of an elongated slightly tapered lapping needle of round cross section extending through the perforation and contacting said tapered entrance and exit portions, causing said tool first to dwell at a predetermined angle to the longitudinal axis of the die perforation for a predetermined time interval and later causing said tool to dwell in a position substantially coincident with said longitudinal axis of the die for a determined time interval, whereby the perforation in the die is accurately contoured to conform to two straight-walled outwardly flaring frusto-conical entrance and exit portions separated by an intermediate straight-walled substantially cylindrical bearing portion.

DANIEL D. SYMMES.
